5,871.—Hot-Air Furnace.—WILLARD TWITCHELL, Syracuse, N. Y.—Patent No. 130,729, dated September 14, 1872. Application filed March 4, 1874.

The construction of the fire-chamber, the magazine, and the smoke-pipe in a single casting is designed to render the escape of gas into the heating-chamber impossible.

Claim.—1. The combination and arrangement of the sheet-metal concentric walls *b c d* with and surrounding the chamber of combustion, forming three concentric air-chambers, as and for the purposes specified, by which the air is made to enter at the bottom, and ascend through the space between the outer case *d* and second case *e*, whence it is deflected downward, over the top *f* to the bottom of *b*, and thence upward to the exit pipes at the top, inside of *b*, all as herein specifically described.

2. In combination with the chamber *D*, the fire-pot *A*, magazine *C*, and pipe *C*, cast in one piece, and without a joint, within said chamber *D*, substantially as and for the purposes described.
